DISPLAY STAND

Jacob B. Herman, Brookline, Mass.

Application January 22, 1947, Serial No. 136,310

Term of patent 3½ years

(Cl. D80—9)

To all whom it may concern:

Be it known that I, Jacob B. Herman, a citizen of the United States, residing at Brookline, in the county of Norfolk and State of Massachusetts, have invented a new, original, and ornamental Design for a Display Stand, of which the following is a specification, reference being had to the accompanying drawing, forming a part thereof, in which:

I claim:

The ornamental design for a display stand, substantially as shown.

JACOB B. HERMAN.
